CLOSURE LATCH AND GUARD

William J. Christie, Tulsa, Okla.

Application November 29, 1939, Serial No. 306,729

1 Claim. (Cl. 292—87)

The invention relates to closure latches and guards particularly adapted for use in connection with the free end of a sleeve and constructed in a manner whereby access to the latch is prevented when the screen is closed and the window sash is in lowered position.

A further object is to provide a screen latch comprising an inverted housing secured to the lower rail of the screen and having an apertured spring latching arm therein adapted to be sprung upwardly over a keeper lug carried by a window sill and to receive said lug in its aperture when the screen is in closed position.

A further object is to provide the outer end of the housing with means whereby access may be had with the finger for springing the latch to open position, and allowing the screen to be opened when the lower window sash is raised. The lower window sash forms means for preventing access to the latching spring when the sash is closed.

A further object is to provide the spring latching arm with an upwardly extending portion engaging the inner wall of the housing and conforming to the shape thereof, thereby allowing the housing and arm to be secured to the screen by a single screw.

A further object is to provide the outer end of the spring latch arm with a curved upwardly extending portion adapted to engage the sill carried keeper lug and to cam over said lug when the screen is closed so the lug will be received in the aperture thereof.

A further object is to provide a hinged closure for the outer end of the latch housing and provided with a notch through which the keeper lug passes to latching position, and at the same time further preventing access to the spring latch arm by an unauthorized person inserting an instrument within the housing.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a detailed perspective view of a portion of the lower rail of a screen, showing the latching device applied thereto.

Figure 2 is a vertical transverse sectional view through a portion of a conventional form of window frame, the latching device and a portion

of the screen, showing the screen in various positions approaching a closed position.

Figure 3 is a view similar to Figure 2, showing the screen closed and latched.

Figure 4 is a detail perspective view of a modified form of latch housing.

Figure 5 is a detailed perspective view of a portion of a window sill showing the keeper lug carried thereby.

Referring to the drawing, the numeral 1 designates the sill of a conventional form of window frame and 2 the lower rail of a conventional form of lower window sash 3.

It is the present practice to secure the lower rail 4 of a top hinge screen 5 to the window sill by conventional hooks and eyes, however an unauthorized person has only to cut the screening 6 and reach in and unhook the screen. In the present device the latching means is entirely housed and access has to be had thereto through the opening 7 of the housing 8 when the lower sash 3 is raised, the rail 2 of which substantially forms a closure for the housing.

Secured within the housing 8 by means of a single screw 9 is a spring latch 10. The spring latch 10 extends outwardly in relation to the housing 8 and terminates in an upwardly and outwardly extending portion 11 in the path of the keeper lug 12, so that when the screen is moved to the full line position shown in Figure 2, the portion 11 of the spring latching arm will engage the keeper lug 12 and will be flexed upwardly until the lug 12 is received within the aperture 13 of the latching arm, clearly shown in Figure 3. The inner end of the spring arm 10 terminates in an upwardly extending portion 14 engaging the inner wall 15 of the housing, therefore it will be seen that a single screw 9 may be used for securing both the latching arm and housing to the screen rail 4, and as the portion 14 conforms substantially to the curvature of the wall 15, the spring latching arm 10 will be prevented from pivotal displacement, see Figure 1.

Referring to Figure 3, it will be seen that when it is desired to release the screen from the inside of the frame, it will only be necessary for the operator to unlatch the lower sash 3 and move the same upwardly. After the sash 3 has been raised the operator can insert his finger under the free end of the spring latching arm 10 for disengaging the same from the keeper lug 12 and then the screen can be swung outwardly on its top supporting hinges. When the lower sash is closed the lower rail 2 will prevent the inser-

tion of a tool into the open end of the housing by an unauthorized person. It will be noted the keeper lug 12 is carried by a plate 16 secured to the window sill 1 by means of screws 17, and when the screen is closed the housing 8 also houses the plate 16 and screws 17 so that access can not be had thereto. The same is true of the screw 9.

Referring to the modified form of housing shown in Figure 4, the operation and construction is the same as shown in Figure 1, excepting the outer end of the housing is provided with a hinged closure 18 having a recess 19 therein for allowing passage of the keeper lug 12. Closure 18 forms additional means for preventing insertion of a tool for opening the screen from the outside. Although the device has been described in connection with a screen having an overhead hinged mounting, it is obvious it could also be used in connection with a screen having a side hinge mounting and applicant does not limit himself in this particular.

From the above it will be seen that a screen

latch is provided which is simple in construction, secured in place on the screen by a single screw and housed so that an unauthorized person will be prevented from reaching the latch and releasing the same when the screen is closed and the window sash in lowered position.

The invention having been set forth what is claimed as new and useful is :

The combination with a window frame having a sill, a slideable sash within said frame and cooperating with the sill, a screen portion movable towards and away from the sill, of latching means for said screen, said latching means comprising an apertured spring arm carried by the screen, a lug carried by the sill in the path of said spring keeper arm and forming means over which the spring arm cams for receiving the keeper lug in the aperture thereof, a housing, an inner wall carried by the housing, a registering member with said wall carried by the spring arm and a single screw extending through said registering member and housing wall into the screen.

WILLIAM J. CHRISTIE.
